United States Patent Office

Des. 183,610

Patented Sept. 30, 1958

183,610

HOBBY HORSE

William H. Horgan, Mound, Minn., assignor to Molded Products, Inc., Maple Plain, Minn., a corporation of Minnesota

Application December 4, 1957, Serial No. 48,767

Term of patent 14 years

(Cl. D34—15)

FIG. 1

FIG. 3

Fig. 1 is a perspective view of a hobby horse showing my new design and viewed from the right side thereof.

Fig. 2 is a perspective view similar to Fig. 1 and viewed from the left side thereof.

Fig. 3 is a plan view of the hobby horse shown in Figs. 1 and 2.

I claim:

The ornamental design for a hobby horse, as shown.
